UNITED STATES PATENT OFFICE.

ELMER G. LEACH AND CLARENCE R. WADDLE, OF OLYMPIA, WASHINGTON; SAID
WADDLE ASSIGNOR TO SAID LEACH.

HOSE-TURNING DEVICE.

Application filed June 15, 1925. Serial No. 37,145.

To all whom it may concern:

Be it known that we, ELMER G. LEACH and CLARENCE R. WADDLE, citizens of the United States, residing at Olympia, in the county of Thurston and State of Washington, have invented certain new and useful Improvements in Hose-Turning Devices, of which the following is a specification.

Our invention relates to improvements in hose turning devices and the object of our invention is to provide a hose turning device of cheap and simple construction that is efficient in operation and that will save much time and labor in turning socks, stockings and similar tubular articles that are being laundered.

Another object is to provide a simple and efficient hose turning device in combination with a clothes stick of the form commonly used in domestic laundries, said hose turning device comprising a ball of larger diameter than the clothes stick rotatably mounted on one end of said clothes stick.

Other and more specific objects will be apparent from the following description taken in connection with the accompanying drawings.

In laundering hosiery and other tubular articles as the sleeves and legs of garments especially small children's garments it is common practice to turn the article that is being laundered so that it may be more thoroughly cleansed. These articles are often small enough so that it is very difficult to insert the hand into the same when the article or the hand, or both, are wet thus making it very difficult to turn the article. Our invention overcomes this difficulty by providing a device that may be quickly and easily thrust into an article, as a sock or stocking without danger of damaging the article and that may be caused by a simple twisting movement of the hand to engage with the article in such a manner that when the device is withdrawn the article will be reversed or turned inside out.

In a device of this nature that is used by the ordinary housewife for domestic laundry work it is necessary that the device be comparatively simple to manipulate and free from complicated mechanism and it is very desirable that said device be capable of being used as a clothes stick.

With the above and other objects in view, the invention consists in the novel construc-

tion, adaptation and combination of parts as will be more clearly hereinafter described and claimed.

In the drawings Figure 1 is a view in elevation of a combined hose turner and clothes stick constructed in accordance with our invention.

Fig. 2 is a mid-sectional view on a larger scale through the hose turning device.

Figs. 3 and 4 are somewhat pictorial views illustrating the operation of the device in turning hosiery.

Like reference numerals designate like parts throughout the several views.

In the drawings 5 designates a relatively long, preferably cylindrical, piece of wood that may serve as a handle for a hose turner and that is provided on one end with an integral knob 6 whereby it may also serve as a clothes stick for the purpose of handling clothes in hot water as is ordinary in home laundry work.

The hose turning device proper comprises a knob 7, of larger diameter than the handle 5, rotatably mounted on a screw 8 that is screwed into the end of said handle and extends axially therefrom. The knob 7 is preferably of oval shape, or may be substantially cylindrical except at the end that abuts against the end of the handle 5 where said knob is flat as at 9 and overhangs or projects beyond the periphery of the handle to afford an annular shoulder 10 for engaging an object of a sock or stocking that is to be turned as hereinafter described. The knob 7 is bored from the outer end inwardly to afford a chamber 11 wherein the head of the screw 8 may be operatively disposed. A compression spring 12 is provided on the screw 8 within the chamber 11 to keep the knob 7 always tightly pressed against the end of handle 5 and afford sufficient friction to prevent the knob 7 from rotating too easily. This friction is necessary to the proper operation of the device and the spring is necessary to keep the friction always constant regardless of wear and expansion and shrinkage due to the parts, which are ordinarily made of wood, becoming wet and drying out.

A bushing 13 of mushroom shape is preferably provided in the bottom end of the chamber 11 to form a thrust bearing for the end of the spring 12 and to form a bearing for relative rotation between the

knob 7 and screw 8. The outer end of opening 11 is preferably closed by a plug 14 which may be cemented therein by water-proof cement or otherwise rigidly secured 5 and which forms a part of the rounded end of the knob.

In use the device is thrust into a sock or stocking 15 until the knob 7 rests in the toe of such sock or stocking and a slight 10 twist, usually from a quarter to a half turn is imparted to the knob 7 and toe of the sock or stocking to cause the sock or stocking to draw around the shoulders 10 of such knob as indicated at 16 in Fig. 3. The upper end of the sock or stocking is then 15 grasped and the handle 5 drawn out of the same as shown in Fig. 4, reversing said sock or stocking with one movement. As the handle 5 is drawn out the knob will automatically 20 release the toe of the sock or stocking without damaging the same. The knob 7 is smooth on the outside and may be readily inserted into a wet sock or stocking without difficulty and without danger 25 of damaging the sock or stocking.

The spring 12 always serves to compensate for all wear and swelling or shrinking of the parts and holds the knob 7 frictionally so that it always offers just enough resistance to turning to stay where it is set 30 and operate efficiently without releasing the sock or stocking.

This hosiery turning device being incorporated into a clothes stick which is ordinarily a part of the equipment of a household laundry is always readily accessible for use and does not even add an extra article to the usual equipment. This turning device may also be used to advantage for 35 turning the sleeves and legs of garments that are being laundered, especially children's garments in which the sleeves and legs are so small as to make it difficult to insert the hand thereinto.

The foregoing description and accompanying drawings clearly disclose a preferred embodiment of our invention but it will be understood that this disclosure is merely illustrative and that such changes 50 in the invention may be resorted to as are within the scope and spirit of the following claims.

We claim:

1. In a turning device of the class described, a handle, and a knob rotatably mounted on the end of said handle, said

knob being of larger diameter than said handle and affording at its end adjacent said handle an unobstructed annular shoulder for engagement with an article to be turned. 60

2. In a turning device of the class described, a handle, a bearing member extending axially from the end of said handle and a knob rotatably mounted on said bearing member, the rear end of said knob being larger than the adjacent end of said handle and forming an annular shoulder for engagement with an object to be turned. 65

3. In a hose turning device, a handle, a knob on the end of said handle, rotatable co-axially of said handle, said knob being larger than the adjacent end of said handle and friction means for retarding the rotation of said knob. 70

4. In a turning device, a handle, an axial pivot on the end of said handle, a knob rotatable on said pivot, the end of said knob adjacent said handle being larger than the end of said handle and affording an annular overhanging flange behind which a tubular article may engage when said knob is inserted in said tubular article and turned and friction means retarding the turning of said knob on said handle. 75

5. In a device of the class described a cylindrical clothes stick and a knob pivoted on one end of said clothes stick for rotation axially relative to said clothes stick said knob having a rounded forward end and a substantially flat rear end that rests against and projects beyond the end of said clothes stick and forms an annular shoulder for engagement with an article to be turned. 80

6. In a hose turning device of the class described a handle, a knob rounded on one end and flat on the other end and having an axial hole that is counterbored to a larger diameter from the rounded end inwardly, a pivot screw arranged to be inserted 100 through said knob and screwed axially into the end of said handle, the head of said screw being operatively disposed in said counterbore, a compression spring on said screw for urging the flat end of said knob 105 against the end of said handle and a closure for the outer end of said counterbore.

The foregoing specification signed at Olympia, Washington, this 2nd day of June, 1925.

ELMER G. LEACH.
CLARENCE R. WADDLE.
